FIRING MECHANISM FOR FIREARMS

Frank F. Burton, Mount Carmel, Conn., assignee
or to Western Cartridge Company, New Haven,
Conn., a corporation of Delaware

Application April 6, 1939, Serial No. 266,280

6 Claims. (Cl. 42—17)

The present invention relates to improvements in the firing-mechanism of firearms, that is to say, improvements in the mechanism by means of which the operation of a trigger, or its equivalent, effects the discharge of the firearm.

One of the objects of the present invention is to provide a superior firing-mechanism for firearms which is both economical to manufacture and reliable in operation.

A further object of the present invention is to provide a superior firing-mechanism for firearms so constructed and arranged with respect to other features of the firearm in which it is incorporated, as to be readily assembled and disassembled.

Another object of the present invention is to provide a superior firing-mechanism for firearms so constructed and arranged as to be suitable for use in a bolt-action firearm having a removable receiver-plug so as not to interfere with the insertion and removal of the latter.

Still another object of the present invention is to provide a superior firing-mechanism suitable for use in a take-down firearm and which is characterized by its freedom from derangement when the firearm is taken down and which may be relied upon to function correctly when the stock-unit and the barrel-unit of a firearm are reassembled.

With the above and other objects in view, as will appear to those skilled in the art from the present disclosure, this invention includes all features in the said disclosure which are novel over the prior art and which are not claimed in any separate application.

In the accompanying drawings in which certain modes of carrying out the present invention are shown for illustrative purposes:

Fig. 1 is a view in side elevation of a bolt-action take-down firearm embodying the present invention;

Fig. 2 is a view of the central portion of the firearm shown mainly in vertical central-longitudinal section and partly in side elevation;

Fig. 3 is a transverse sectional view taken on the line 3—3 of Fig. 2;

Fig. 4 is a similar view taken on the line 4—4 of Fig. 2;

Fig. 5 is a broken transverse sectional view taken on the line 5—5 of Fig. 2 but on a larger scale than the same;

Fig. 6 is a view in vertical central-longitudinal section corresponding to Fig. 2 but showing the positions which the parts assume when the reciprocating breech-bolt is rearward of its breech-closing position;

Fig. 7 is a view of the rear portion of the barrel-unit showing the same mainly in side elevation and partly in vertical section;

Fig. 8 is an underside view thereof;

Fig. 9 is a view of the central portion of the stock-unit detached and shown mainly in side elevation and partly in vertical central-longitudinal section;

Fig. 10 is a top or plan view thereof;

Fig. 11 is a top or plan view of the receiver-plug and the parts assembled therewith, detached;

Fig. 12 is an underside view thereof;

Fig. 13 is a perspective view of the trigger;

Fig. 14 is a perspective view of the transmitting-member viewed mainly from the side;

Fig. 15 is a similar view but viewing the transmitting-member mainly from below; and

Fig. 16 is a perspective view of the sear.

The particular take-down bolt-action firearm herein chosen for the illustration of the present invention includes two main units, namely, a stock 20 and a barrel-unit comprising principally a receiver 21 and a barrel 22 rigidly attached to and forwardly extended from the said receiver. The barrel-unit comprising the receiver 21 and the barrel 22 is detachably secured to the stock 20 by means of an attaching-screw 23 extending vertically through the stock 20 at a point immediately forwardly of the front-end of the receiver 21. The head-end of the attaching-screw 23 just referred to, is seated in an escutcheon 24 mounted in the under face of the stock 20 (Figs. 2 and 6). The threaded upper end of the said attaching-screw 23 extends into threaded engagement with a barrel-lug 25 depending from the rear portion of the barrel 22 and forming a rigid feature thereof.

The receiver 21, in the construction shown, is of tubular form with its exterior cylindrically-contoured save for certain cuts therein. The said receiver 21 is formed interiorly with an axial cylindrically-contoured bolt-receiving passage 26 extending throughout the length of the receiver and at its forward end receiving the threaded rear end of the barrel 22.

Fitting into the rear portion of the bolt-receiving passage 26 in the receiver 21 is a cylindrically-contoured receiver-plug 27 which is removably retained in place in the said bolt-receiving passage in a manner as will hereinafter appear. Intermediate the forward end of the receiver-plug 27 and the rear end of the barrel 22, is a reciprocating breech-bolt 28 which, generally considered, is cylindrically contoured and is formed at its rear end with an annular bear-

ing-flange 29 and adjacent its forward end with a similar bearing-flange 30. Both of the bearing-flanges 29 and 30 just referred to have a smooth sliding fit with respect to the surface of the bolt-receiving passage 26 in the receiver 21, so as to provide both support and guidance for the breech-bolt 28 in its reciprocating movement within the said receiver.

In its lower portion, the breech-bolt 28 is formed with a longitudinal passage 31 in which extends the forward end of a spring-guiding plunger 32 having its rear end provided with a head 33 and seated in a forwardly-opening socket 34 extending longitudinally of the receiver-plug 27 in axial alignment with the longitudinal passage 31 in the breech-bolt 28. Encircling the spring-guiding plunger 32 is a helical breech-bolt-return spring 35 thrusting at its forward end against the front end-wall of the passage 31 and at its rear end bearing against the forward face of the head 33 of the said spring-guiding plunger 32, as is especially well shown in Figs. 2 and 6 of the accompanying drawings.

Above its longitudinal axis and in parallelism with the longitudinal passage 31 therein, the breech-bolt 28 is formed with a firing-plunger passage generally designated by the reference character 36 and having a relatively-small-diameter forward portion 37 and a relatively-large-diameter rear portion 38 which latter opens through the rear face of the said breech-bolt and which former opens through the forward face thereof.

Reciprocating in the firing-plunger passage in the breech-bolt 28 is the forward portion of a reciprocating firing-plunger or striker generally designated by the reference character 39 and including a cylindrically-contoured bearing-portion 40 located about midway of its length and bearing in the rear portion 38 of the firing-plunger passage 36. Projecting forwardly from the bearing-portion 40 of the firing-plunger 39 is a firing-point 41 reciprocating in the forward portion 37 of the said passage 36. Projecting rearwardly from the bearing-portion 40 of the firing-plunger 39 is a shank 42 which is adapted to reciprocate in a bore 43 formed in the receiver-plug 27, before referred to, in axial alignment with the firing-plunger passage 36 in the breech-bolt 28.

Positioned intermediate the forward face of the receiver-plug 27 and the rear face of the bearing-portion 40 of the firing-plunger 39 is a helical firing-spring 44 encircling that portion of the shank 42 of the said firing-plunger which happens to be located forwardly of the receiver-plug 27 at any given time.

The shank 42 of the firing-plunger 39 is formed, as shown, with a cocking-shoulder 45 which is engageable by a sear-nose 46 depending from the forward end of a sear 47 which is preferably formed of sheet-metal. The said sear is formed on each of its respective opposite sides with a depending side-flange 48 suitably perforated adjacent their respective rear ends for the reception of a transverse pivot-pin 49 about which the sear as a whole is adapted to rock and which is mounted in the receiver-plug 27 so as to extend laterally across an upwardly-opening cavity 50 in the latter. The rearmost portion of the sear 47 is pressed outwardly to thus urge the sear-nose 46 inwardly, by means of a helical sear-spring 51 seated in an upwardly-opening pocket 52 in the receiver-plug 27.

Adjacent their respective forward ends each of

the side-flanges 48—48 of the sear 47 is formed with a downwardly-extending actuating finger 53 laterally spaced from its companion actuating-finger sufficiently to project downwardly along the adjacent side of the path of movement of the firing-plunger 39, the breech-bolt-return spring 35 and the spring-guiding plunger 32 as is shown especially well in Figs. 3 and 6. The said actuating-fingers 53—53 project downwardly through a vertical-passage 54 leading downwardly from the cavity 50 in the upper portion of the receiver-plug 27 and intersecting at its lower end a cavity 55 in the lower portion of the said receiver-plug.

Extending diametrically across the rear portion of the receiver-plug 27 is a locking-bolt passage 56 receiving a reciprocating locking-bolt 57, the respective opposite ends of which are, under normal conditions, entered into locking-passages 58 one of which is formed in each of the respective opposite side-walls of the receiver 21 in line with the locking-bolt passage 56 in the receiver-plug 27. Adjacent its right end the locking-bolt 57 is formed with a contracted neck 59 which is adapted to be brought into registration with a releasing-passage 60 (Figs. 1 and 5) when the locking-bolt 57 is moved from the position in which it is shown in full lines in Fig. 5 into the position in which it is indicated by broken lines in the same figure. The said releasing-passage 60 leads from the right hand locking-passage 58 to the rear edge of the receiver 21 so that when the locking-bolt 57 is moved axially of itself to bring the neck 59 in registration with the said releasing-passage 60, the said locking-bolt and the receiver-plug by which it is carried may be withdrawn through the rear end of the receiver.

About midway of its length the locking-bolt 57 is formed with a vertical clearance-passage 61 through which extends a vertical limiting-pin 62 carried by the receiver-plug 27. Arranged axially with respect to the locking-bolt and intersecting the clearance-passage 61 therein is a spring-pocket 63 receiving a helical-spring 64 which presses against the limiting-pin 62 and exerts a yielding effort to maintain the locking-bolt 57 in its locking position as is indicated by full lines in Fig. 5.

Partly in registration with the cavity 55 in the under face of the receiver-plug 27, the receiver 21 is formed with a clearance-cut 65 across the forward-end of which extends a pin 66 rigidly mounted in the adjacent portion of the said receiver. Mounted with capacity for both pivotal and bodily longitudinal movement in the clearance-cut 65 and upon the pin just above referred to, is a transmitting-member generally designated by the reference character 67 and preferably formed of sheet-metal. In a manner as will hereinafter appear, the said transmitting-member acts to transmit the movement of a trigger 68 to the sear 47 before referred to.

The transmitting-member 67, just above referred to, is provided on each of its respective opposite sides with a side-flange 69, each of which is provided at its rear end with an upstanding actuating-finger 70 adapted to engage with and upwardly-press one of the actuating-fingers 53 of the sear 47. Each of the side-flanges 69—69 is provided adjacent its forward end with an upwardly- and forwardly-inclined guide-slot 71 through which the pin 66 in the receiver 21 extends to provide for both the rocking and limited bodily movement of the said transmitting-member 67 with respect to the receiver 21.

The rear end of the transmitting-member 67 is formed with a bifurcated guide-arm 72 which straddles the grooved intermediate-portion 73 of a guide-screw 14 threaded into the bottom-wall of the receiver 21. The said guide-screw 14 serves to clamp to the under face of the receiver 21, the rear end of a sheet-metal spring 75 which is pre-set so that its center portion is depressed to bear against the adjacent face of the transmitting-member 67 and which has its forward end extended through an apertured tongue 76 at the forward end of the said transmitting-member. As thus constructed and arranged, the spring 75 yieldingly tends to depress the rear end of the transmitting-member 67 and to raise the forward end thereof within the limits of movement permitted by the guide-slots 71-71 and the guide-screw 14.

The trigger 68 before briefly referred to, is preferably formed of sheet metal and comprises two laterally spaced-apart T-shaped side-bars 77-77 interconnected at their upper rear portions by a transversely-extending actuating-bar 78 which is adapted to engage the under face of the transmitting-member 67 for shifting the same in a manner as will be hereinafter described. The lower ends of the spaced-apart side-bars 77-77 are integrally united by a curved fingerpiece 79 projecting below the under surface of the stock 20 into a space substantially circumscribed by a loop-like trigger-guard 80 secured to the under face of the stock 20.

The upper portion of the trigger 68 is accommodated in an upwardly-opening cavity 81 in the stock 20 and the intermediate portion of the said trigger extends downwardly through a clearance-passage 82 also formed in the said stock and interconnecting the cavity 81 therein with the under face of the stock 20.

The trigger 68 is mounted with capacity for pivotal movement in the stock 20 by means of a trigger-pin 83 extending through the perforated forward ends of the complementary side-bars 77-77 and into rigid engagement with the flanking portions of the said stock 20.

The trigger 68 is yieldingly turned in a clockwise direction around the trigger-pin 83 so as to maintain its actuating-bar 78 in light engagement with the under face of the transmitting-member 67, by a trigger-spring 84 preferably formed of spring-wire and extending around the trigger-pin 83 before referred to, and having companion upper arms engaging the under edge of the actuating-bar 78 and having its opposite U-shaped portion resting upon the upper surface of a magazine-tube 85.

It may be explained in this connection that the trigger-spring 84 above referred to is so light in its tension as not to in any way overcome the tension of the heavier sheet-metal spring 75 of the transmitting-member 67, and therefore the said trigger-spring can under no circumstances effect the actuation of the said transmitting-member 67 to in turn effect the discharge of the firearm.

The magazine-tube 85 above referred to extends forwardly and upwardly through the stock 20 and between the respective opposite side-bars 77-77 of the trigger 68 with sufficient freedom to leave the said trigger free of restraint thereby, as shown in Figs. 2, 3 and 9.

For the purpose of illustrating the operation of the firearm herein shown and described, let it be assumed that the receiver-plug 27 is firmly locked in place in the receiver 21 by means of the

locking-bolt 57 and that the breech-bolt 28 is in its breech-closing position, as indicated particularly well in Fig. 2, and let it be assumed further that the firing-plunger 39 is cocked as is also shown in the said figure. The firearm is thus in condition for being discharged upon the actuation of the trigger 68.

Now when rearward pressure is applied to the fingerpiece 79 of the trigger 68, the said trigger will be rocked about its trigger-pin 83 with the effect in turn of rocking the transmitting-member 67 about its pin 66 thus causing the rear end of the said transmitting-member to rise. The rising movement of the rear end of the transmitting-member 67 will, of course, similarly raise its actuating-fingers 70-70, which latter in turn will lift the depending actuating-fingers 53-53 of the sear 47 and thus cause the said sear to rock in a counterclockwise direction about its pivot-pin 49 against the tension of the sear-spring 51.

The counterclockwise swinging of the sear 47 as just above described will lift the sear-nose 46 thereof out of engagement with the cocking-shoulder 45 of the firing-plunger 39 to thus release the firing-plunger to the action of the firing-spring 48. The said firing-spring 48 will "snap," so to speak, the said firing-plunger 39 forwardly and will effect the discharge of the firearm.

After the discharge of the firearm as above described, the breech-bolt may be moved rearwardly against the tensions of the breech-bolt-return spring 35 and the firing-spring 48 to extract and eject the cartridge-case of the just-fired cartridge preparatory to the insertion of a fresh cartridge in the usual manner of bolt-action firearms.

Immediately following the start of its rearward movement from the position in which it is shown in Fig. 2, the breech-bolt 28 will engage its sloping lower rear corner 86 with the rounded forward upper corners of the side-flanges 69-69 of the transmitting-member 67 with the effect of depressing the forward end of the said transmitting-member and thereby moving the same rearwardly in a path controlled by the inclined guide-slots 71-71 until the said transmitting-member is shifted from the position in which it is shown in Fig. 2 into the position in which it is shown in Fig. 6. The continued rearward travel of the breech-bolt 28 will cause the same to override the forward portion of the transmitting-member 67 and thus effectively retain the said transmitting-member in its rearmost position, until such time as the breech-bolt is again in its breech-closing position as indicated in Fig. 2.

The rearward movement of the transmitting-member 67 as above described, serves to shift its upstanding actuating-fingers 70-70 to the rear of the depending actuating-fingers 53-53 of the sear 47 and therefore out of coacting relationship therewith. If the trigger 68 should be pulled while the breech-bolt 28 is out of its breech-closing position and hence while the transmitting-member 67 is in its rearmost position, the sear 47 will not be actuated since the actuating-fingers of the transmitting-member will merely rise idly behind the actuating-fingers 53-53 of the said sear.

From the foregoing it follows, therefore, that even though the firing-plunger 39 be cocked, the sear 47 cannot be actuated to release the said firing-plunger when the transmitting-member 67 is in its rearmost position as shown in Fig. 6

as a result of its being shifted by the rearward travel of the breech-bolt 28.

Thus, in a simple and effective manner, the firearm is rendered safe against unintentional discharge whenever the breech-bolt 28 is in other than its breech-closing position.

By so constructing the sear and associated parts so that the said sear is situated on the opposite side of the firing-plunger from the transmitting-member 67 and the trigger 68, an exceedingly compact, reliable and effective structure results which may be produced at a low cost for manufacture.

Furthermore, by mounting the sear in a removable receiver-plug the said sear may be conveniently and economically assembled with the firearm-structure and may be conveniently and readily brought into the open for inspection, lubrication, adjustment or repair.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. A bolt-action firearm-construction including in combination: a receiver; a breech-bolt reciprocatable in the said receiver and having a portion engageable with a transmitting-member; a reciprocating firing-plunger movable in the said breech-bolt; a trigger located below the said reciprocating firing-plunger; a sear pivotally mounted within the said receiver intermediate the respective opposite ends thereof and having a firing-plunger-restraining portion located above the said reciprocating firing-plunger and releasably engageable therewith; and a transmitting-member mounted in and connected to the said receiver with capacity for both rocking and bodily longitudinal movement and in position to be rocked by the said trigger when the latter is actuated to in turn actuate the said sear and in position to be engaged by a portion of the said breech-bolt in the rearward movement of the latter to be moved longitudinally rearward thereby to respectively cause the said sear to be disengaged from the said firing-plunger by the actuation of the said trigger and the said transmitting-member, and to cause the said transmitting-member to be moved by the said breech-bolt out of actuating position with respect to the said sear and free the same to engage with the said firing-plunger.

2. A bolt-action firearm-construction including in combination: a receiver; a breech-bolt reciprocatable in the said receiver and having a portion engageable with a transmitting-member; a reciprocating firing-plunger movable in the said breech-bolt; a trigger located below the said reciprocating firing-plunger; a sear pivotally mounted within the said receiver intermediate the respective opposite ends thereof and having a firing-plunger-restraining portion located above the said reciprocating firing-plunger and engageable therewith, the said sear also having a depending actuating-finger extending downwardly and to one side of the said firing-plunger between the same and the adjacent side wall of the said receiver; and a transmitting-member mounted in and connected to the said receiver with capacity for

both rocking and bodily longitudinal movement and in position to be rocked by the said trigger when the latter is actuated to in turn actuate the said sear and in position to be engaged by a portion of the said breech-bolt in the rearward movement of the latter and moved longitudinally rearwardly thereby to respectively cause the said sear to be disengaged from the said firing-plunger by the actuation of the said trigger and the said transmitting-member, and to cause the said transmitting-member to be moved by the said breech-bolt out of actuating position with respect to the said sear and free the same to engage with the said firing-plunger.

3. A bolt-action firearm-construction including in combination: a receiver; a breech-bolt movable in the said receiver; a firing-member also movable in the said receiver; a sear located above the said firing-member and having two laterally-spaced-apart actuating fingers respectively located on opposite sides of the said firing-member and extending downwardly on either side thereof; and a trigger located below the said firing-member and operatively connected to the said sear to actuate the same through the intermediary of the depending actuating-fingers of the latter.

4. A bolt-action firearm-construction including in combination: a receiver; a suspension-pin carried by the said receiver; a breech-bolt reciprocatable in the said receiver; a firing-member also movable in the said receiver; a trigger located below the said firing-member; a sear located above the said firing-member; a transmitting-member having a downwardly and rearwardly inclined guide-slot receiving the said suspension-pin, the said transmitting-member being positioned to be engaged by a portion of the said breech-bolt for being moved thereby in a path determined by the said guide-slot and the said suspension-pin; spring-means yielding urging the said transmitting-member in opposition to the movement imparted to it by the said breech-bolt; means operatively interconnecting the said transmitting-member with the said sear; and a trigger for actuating the said transmitting-member to in turn actuate the said sear.

5. A bolt-action firearm-construction including in combination: a receiver having a breech-bolt-receiving passage therein and opening through the rear face thereof; a breech-bolt movable in the breech-bolt-receiving passage in the receiver; a receiver-plug releasably installed in the said receiver and plugging the rear end of the breech-bolt-receiving passage and projecting forwardly therein to the rear of the said breech-bolt therein; a firing-plunger reciprocatable in both the said breech-bolt and in the said receiver-plug; the said receiver-plug being operatively connected to the said breech-bolt for removal of the latter with the former as a unit at the rear of the said receiver; a sear carried by the said receiver-plug at a point above the path of movement of the said reciprocating firing-plunger; a trigger located below the said firing-plunger; and means passing to one side of the said firing-plunger between the same and the adjacent side wall of the said receiver and operatively interconnecting the said trigger with the said sear.

6. A bolt-action firearm-construction including in combination: a receiver having a breech-bolt-receiving passage therein and opening through the rear face thereof; a breech-bolt

movable in the breech-bolt-receiving passage in the said receiver; a receiver-plug releasably installed in the said receiver and plugging the rear end of the breech-bolt-receiving passage and projecting forwardly therein to the rear of the 5 said breech-bolt therein; a firing-plunger reciprocatable in both the said breech-bolt and in the said receiver-plug; the said receiver-plug being operatively connected to the said breech-bolt for removal of the latter with the former 10 as a unit at the rear of the said receiver; a sear carried by the said receiver-plug at a point above

the said firing-plunger in position to control the same; a transmitting-member mounted in the said receiver and located below the said firing-plunger; means extending to one side of the said firing-plunger between the same and the adjacent side wall of the said receiver and operatively interconnecting the said transmitting-member with the said sear; and a trigger constructed and arranged to actuate the said transmitting-member to cause the same to in turn actuate the said sear.

FRANK F. BURTON.
